CLAIM

The ornamental design for an extension ring with narrow flange, as shown.

DESCRIPTION

FIG. 1 is a front-right perspective view of an extension ring with narrow flange in accordance with the present design; FIG. 2 is a rear-left perspective view of the extension ring with narrow flange shown in FIG. 1;

FIG. 3 is a front view of the extension ring with narrow flange shown in FIG. 1;

FIG. 4 is a rear view of the extension ring with narrow flange shown in FIG. 1;

FIG. 5 is a top plan view of the extension ring with narrow flange shown in FIG. 1;

FIG. 6 is a bottom plan view of the extension ring with narrow flange shown in FIG. 1;

FIG. 7 is a left side view of the extension ring with narrow flange shown in FIG. 1; and,

FIG. 8 is a right side view of the extension ring with narrow flange shown in FIG. 1.
